Primary Examiner — Austin Murphy(74) *Attorney, Agent, or Firm* — Birch, Stewart, Kolasch & Birch, LLP(57) **CLAIM**

The ornamental design for a head mounted display device, as shown and described.

DESCRIPTION

FIG. 1 is a perspective view of a head mounted display device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference view thereof showing the state that the user wears the subject design.

The broken lines show unclaimed subject matter only and form no part of the claimed design. The dash-dot broken lines define the bounds of the claimed design and form no part thereof.
